UNITED STATES PATENT OFFICE.

PLAZI B. FRIBURK AND FELIX A. BORER, OF LE SUEUR, MINNESOTA.

SULKY-PLOW.

SPECIFICATION forming part of Letters Patent No. 373,450, dated November 22, 1887.

Application filed June 25, 1887. Serial No. 242,525. (No model.)

To all whom it may concern:

Be it known that we, PLAZI B. FRIBURK and FELIX A. BORER, citizens of the United States, residing at Le Sueur, in the county of 5 Le Sueur and State of Minnesota, have invented a new and useful Improvement in Sulky-Plows, of which the following is a specification.

Our invention relates to an improvement in 10 sulky-plows; and it consists in the peculiar construction and combination of devices, that will be more fully set forth hereinafter, and particularly pointed out in the claims.

In the drawings, Figure 1 is a perspective 15 view of a sulky-plow embodying our improvements. Fig. 2 is an end elevation of the same. Fig. 3 is a detail view of the clevis.

A represents the axle, which is bent downwardly near one extremity, as at B, and upwardly at the opposite extremity, as at C, thereby forming vertical arms. From the lower end of the arm B projects a spindle, B', on which is mounted a supporting-wheel, D, and from the upper end of the arm C projects a 25 spindle, C', on which is mounted a similar supporting-wheel, E. From the front side of the axle projects a downwardly-inclined frame, F, comprising the side bars, f, and the front connecting cross-bar, f'. From the front 30 side of the said cross-bar projects an arm, G.

H represents a spring-bar, which has its lower end attached to the cross bar f', and to the upper end of the said spring-bar is attached a seat, I, for the driver.

K represents a plow, which may be of any 35 preferred construction, and is provided with the beam L and the usual handles, M. To the rear end of the beam is attached a clevis, N. The said clevis is made in the shape of an open 40 link, so as to embrace the beam, and is provided on its rear side with an eye, O.

P represents a draft-chain, which is attached to the front end of the arm G of the sulky, and to the front end of the said chain 45 is attached a hook, R, which is adapted to engage the eye of the clevis, and thus connect the sulky to the rear end of the plow. From the front end of the sulky-frame depends a standard, S, in which is mounted a support- 50 ing-wheel, T.

The operation of our invention will be very readily understood. The team is hitched to the plow in the usual manner, and the plowman sits upon the seat I, places his feet upon the cross-bar f', and grasps the handles of the plow. 55 As the plow is flexibly connected to the sulky-frame, the plowman is easily enabled to guide the plow in any desired course, so as to cause it to clear stumps and obstructions. The wheel D, which is journaled on the spindle of 60 the axle projecting from the depending arm, runs in the furrow made by the plow, and the wheel E on the spindle of the upwardly-projecting arm of the axle runs on the land side, thus maintaining the sulky-frame in a horizontal 65 position.

Having thus described our invention, we claim—

1. The combination of the plow having the 70 clevis N attached to the standard and provided with the rearward-extending eye O, the sulky having the supporting-wheels at its rear end and the small wheel T at its front end, adapted to run directly in rear of the plow, and the chain connecting the said sulky to the 75 eye of the clevis, substantially as described.

2. A sulky adapted to be trailed in rear of a plow to carry the plowman, and comprising the axle having the vertical cranks at opposite ends extending in opposite directions, the 80 supporting-wheels D and E, journaled on the spindles of the said cranks, the frame F, extending from the front side of the axle, and having the depending standard S at its front end, the supporting-wheel T, journaled in the 85 said standard, the curved spring-bar H, having its front end attached to the front of the frame F and its rear end attached to the axle, and the seat I, secured on the said spring-bar, substantially as described. 90

In testimony that we claim the foregoing as our own we have hereto affixed our signatures in presence of two witnesses.

PLAZI B. FRIBURK.
FELIX A. BORER.
